GAS RANGE

Filed March 9, 1929

Inventor:
George E. Pickup
Blindfold, Indiana, U.S.A.
Atty's.

UNITED STATES PATENT OFFICE

GEORGE E. PICKUP, OF NEWARK, OHIO, ASSIGNOR TO THE WEHRLE COMPANY, OF NEWARK, OHIO, A CORPORATION OF OHIO

GAS RANGE

Application filed March 9, 1929. Serial No. 345,688.

The invention relates to gas ranges and has for its aim the provision of a range having a compact arrangement of parts by which a neat and ornamental appearance is presented.

One object of the invention is to provide a novel and improved arrangement whereby certain operating parts are wholly concealed from view.

10 A further object of the invention resides in the provision of a novel form of a concealing member, in which a portion of the front of the range top and a concealing strip depending therefrom are integrally formed, thereby simplifying the construction and enhancing the appearance of the range.

Another object of the invention is to provide a novel construction embodying a single supporting member for mounting the gas 20 manifold and the concealing strip thereon on the range as a compact group which may be readily disassembled.

Another object of the invention is to provide an improved construction of a concealing member which may be conveniently enameled or similarly coated to harmonize with the remaining portions of the range.

Still another object of the invention is to devise an improved structure of this character capable of being cheaply manufactured by casting, quickly and easily assembled in position, and which may be conveniently cleaned.

Other objects and advantages will become apparent in the following description and from the accompanying drawings in which:

Figure 1 is a fragmentary plan view of a range top embodying the invention.

Fig. 2 is a front elevation of the same.

40 Fig. 3 is a plan view of the supporting member.

Fig. 4 is a plan view of the manifold.

Fig. 5 is a plan view of the concealing member.

45 Fig. 6 is a central vertical section on an enlarged scale taken substantially on the lines 6-6 of Fig. 2.

While the invention is susceptible of various modifications and alternative constructions, I have shown in the drawings and have

herein described in detail the preferred embodiment, but it is to be understood that I do not thereby intend to limit the invention to the specific form disclosed, but intend to cover all modifications and alternative constructions falling within the spirit and scope of the invention as expressed in the appended claims.

In illustrating the invention it has been deemed unnecessary to show a complete gas 60 range inasmuch as the invention is capable of application to any type of a range embodying an open flame cooking section.

In the present instance, referring to Fig. 1, the invention is shown in connection with a cooking top embodying a frame comprising side members 10 and 11 and back 12, each formed to provide an inwardly opening rabbeted groove 13 to receive one or more cooking grids 14 of any well known construction. 70 The cooking section in this instance also includes a manifold 15 (see Fig. 6) for supplying fuel gas, a mixing chamber 16 for each burner, and a valve 17 interposed between the manifold and each mixing chamber for 75 controlling the passage of gas to each burner. An operating stem 18, carrying a handle 19 at its outer end, extends forwardly from each valve 17.

Generally speaking, certain objects of the 80 invention are attained by providing a concealing member in the form of a unitary structure, one part of which extends transversely of the front of the range and forms a continuation of the cooking top, while another part of the structure extends downwardly from the first mentioned part to conceal the operating parts of the burner system. Furthermore, the invention contemplates the provision of a single supporting 85 means for both the manifold and the concealing member by which the parts may be compactly arranged in the range and the assembly thereof facilitated.

To this end a supporting bar 20 is arranged to extend across the front of the cooking top between the side frame members 10 and 11. Preferably the supporting bar is channel shaped in cross-section, (see Fig. 6) and is so mounted that the channel faces 100

downwardly. At either end the supporting bar turns rearwardly at right angles to the bar proper and a lug 21, offset from the surface of the bar, is provided on each turned portion for engagement with a complementary lug 22 formed upon the front end of the side frame members 10 and 11. Bolts 24 through registering apertures in the lugs 21 and 22 secure the parts in assembled relation, the offset distance of the lugs 21 being such that the upper surface of the supporting bar 20 lies substantially in the plane of the horizontal face of the rabbeted groove 13 when the parts are assembled. Along either end 10 uprising flanges 25 on the supporting bar 20 constitute continuations of the uprising portions of the side flange members 10 and 11 which designate the vertical face of the rabbeted groove 13.

15 The manifold 15 is preferably so constructed that it may readily be formed from cast metal and comprises an elongated hollow member of substantially rectangular cross-section, (see Fig. 6). One end of the manifold is closed and the other end, as shown at 20, is turned rearwardly a short distance and is screw threaded to receive a conduit (not shown) leading to a suitable source of fuel gas. The manifold is preferably secured detachably to the supporting bar 20 and for this purpose spaced lugs 27, formed integrally upon the manifold, extend laterally and rearwardly therefrom. The lugs 27 are so positioned on the manifold that when they 25 are in underlying relation to the supporting bar 20, the upper surface of the manifold is substantially flush with the upper surface of the supporting bar 20.

30 In order, during assembly, that the manifold may be definitely located in the aforesaid relative position to the supporting bar 20, an upstanding boss 30 on each of the lugs 27 is positioned to enter into the channel of the supporting bar 20 and to abut a complementary boss 31 extending into the channel from the side remote from the manifold. Suitable means, such as bolts 28, (Figs. 2 and 45) extending through registering apertures 29, 29a in the supporting bar 20 and the lugs 27 respectively, detachably secure the manifold to the supporting bar.

50 The concealing member, generally designated 32, see Figs. 1, 2, 5, and 6, comprises an elongated substantially L-shaped piece capable of being easily constructed of cast metal. One leg 33, of the member, constitutes the forward portion of the top of the cooking section and is adapted to be secured to the supporting bar after the manifold has 55 been secured to said bar. Thus, apertures 34, in spaced lugs 35 extending from the free or rear edge of the leg 33, may be brought into registry with appropriately positioned apertures 34a in the supporting bar 20 to receive bolts 36, or the like.

70 The relative position of the supporting bar 20 and the concealing strip 32 is such that the rear edge of the leg 33 at either end abuts the forward ends of the flanges 25 to provide, with the upper surface of the bar 20, a continuation of the rabbeted groove 13 across the front of the stove. Moreover, the thickness of the leg 33 is such that the upper surface thereof is substantially flush with the top face of the frame members 10, 11 and 12. Thus when the cooking grid 14 is properly positioned in the rabbeted groove, the leg 33 constitutes the front top portion of the range.

75 The other leg 37 of the concealing member 32 extends downwardly from the front of the leg 33, and the arrangement of parts is such that this leg lies in front of and completely conceals the manifold 15, valves 17, and other burner operating parts. At appropriate intervals apertures 38 are provided in the leg 37 to permit the operating stems 18 to extend therethrough. If desired, the depending leg may be fashioned to enhance the ornamental appearance of the range front by offsetting the lower portion, as indicated at 80 39, (Fig. 6), a short distance rearwardly and by slightly rounding this offset portion. In addition to its part concealing function, the depending leg 37 also serves as a flame guard, 85 whereby the handles are substantially insulated from the heat of the burners, and the operator is protected in the event a burner back-fires. At either end the forward edge of the concealing member may be shaped to 90 form rounded corners 40 for the cooking top, the depending leg following the curvature to extend rearwardly in conformity with the sides of said top.

95 It will be seen from the foregoing that a 100 concealing member of new and improved form has been provided which may be economically manufactured as a unit in any preferred manner, as by casting. In addition, assembly of the associated parts to form a compact unit is facilitated. Unsightly seams or 105 gaps across the front of the range are eliminated, adding materially to the appearance of the range, and further rendering this portion of the range easy to clean. Moreover, the 110 concealing member in the present construction is capable of being easily enameled to conform to the general color scheme of the range and, since the various operating parts are totally concealed, makes it unnecessary to nickel-plate or otherwise ornament such parts.

115 I claim as my invention:

120 1. In a gas range, the combination of a top frame comprising rear and side members each having an inwardly facing rabbeted groove 125 therein for receiving a cooking grid, a front member extending between the forward ends of said side members with its upper face in the plane of the horizontal faces of said 130

groove and having downwardly offset lugs thereon extending beneath the ends of said side members, means extending through the horizontal faces of the rabbeted grooves and engaging said lugs to secure said front frame member to said side members, a manifold positioned in front of said front frame member with its upper surface in substantially the same plane as the upper surface of said frame member, and having lugs extending rearwardly therefrom beneath said front frame and each engaging said front frame member at points spaced transversely of said member, means extending downwardly through the front frame member and engaging said lugs to secure said manifold in position, and an angular concealing member comprising a horizontal part forming a continuation of said top and having its rear edge portion secured to said front frame member, said rear edge constituting the front vertical face of said rabbeted groove and said horizontal part resting on said manifold along a line spaced forwardly from said rear edge, and a substantially vertical portion depending from said horizontal portion in concealing relation to said manifold.

2. In a gas range, the combination of a cooking top having an upper supporting frame having a U-shaped upper supporting frame comprising rear and side members having an inwardly facing rabbeted groove therein to receive a cooking grid, a front frame member extending between and secured to the forward ends of said side members and having an upper surface forming a continuation of the horizontal face of said rabbeted groove, said front frame member being of an inverted U-shaped cross section, a manifold positioned in front of said front frame member and having an upper surface substantially in the same horizontal plane with the upper surface of said front frame member, said manifold having lugs extending beneath said front frame member and engaging the lower edges thereof, a plurality of bolts extending downwardly through said front frame member and engaging said lugs to hold said manifold in position on said front frame member, and an angular concealing member comprising a horizontal part positioned over said manifold and having its rear edge secured to said front frame member, said rear edge constituting forward vertical faces of said rabbeted groove and said horizontal part resting on said manifold along a line spaced forwardly from said rear edge, said concealing member also having a substantially vertical portion depending from said horizontal portion and serving to conceal said manifold.

3. A gas range having, in combination, a top frame comprising a main portion providing side and rear members, a separately formed supporting member secured at oppo-

site ends to the forward ends of said side members at the undersides thereof, a manifold having rearwardly extending supporting arms detachably secured to the underside of said supporting member, control valves operatively associated with said manifold and having valve operating members extending forwardly therefrom, and an angular concealing member having a relatively flat horizontal part of substantial width and a vertical portion depending from the front edge of said horizontal part below said manifold, the rear edge portion of said horizontal part being secured upon the upper side of said supporting member, said side and rear members being shaped to provide an upwardly and inwardly facing rabbet groove and said concealing member coacting with said front frame member to provide a similar groove, which grooves are adapted to receive and support a utensil-supporting grid.

4. A gas range having, in combination, a top frame comprising a main portion providing side and rear members, a separately formed elongated supporting member secured at opposite ends to the forward ends of said side members at the undersides thereof, a manifold having rearwardly extending supporting arms detachably secured to the underside of said supporting member, and an angular concealing member having a relatively flat horizontal part of substantial width and a vertical portion depending from the front edge of said horizontal part below said manifold, and the rear edge portion of said horizontal part being detachably secured upon the upper side of said supporting member.

5. A gas range having, in combination, a cooking top comprising a frame including side and rear members, a supporting member of inverted channel shaped cross section extending across the front of the stove top with its upper surface offset downwardly from the upper surfaces of the side members, a gas supply manifold having supporting arms detachably secured to the underside of said supporting member and having valve stems projecting forwardly therefrom, and an angular casting comprising a horizontal part of substantial width with its rear edge portion detachably secured on the upper side of said supporting member, said casting further having a substantially vertical part extending downwardly from the forward edge of the horizontal part and being apertured to permit said valve stems to extend therethrough.

In testimony whereof, I have hereunto affixed my signature.

GEORGE E. PICKUP. 125
